UNITED STATES PATENT OFFICE.

WILLIAM C. HUEBNER, OF BUFFALO, NEW YORK.

PLANOGRAPHIC-PRINTING ELEMENT AND PROCESS OF MAKING SAME.

Application filed October 13, 1922. Serial No. 594,371.

In direct planographic printing in which prints are made directly from metal plates, lithographic stones and analogous, hard or unyielding printing surfaces, great difficulty is experienced in attempting to produce high class halftone or similar fine textured work on account of the unavoidable unevenness and rigidity of the printing plates or surfaces, the unevenness of the paper or other print-receiving material and the inking rollers, and the consequent great pressure needed to secure fair printed impressions. The result is a more or less broken impression where the values are lighter than solid color, and the process requires hard, smooth-surfaced paper for printing.

The above-mentioned difficulties are mainly overcome in offset printing by the yielding rubber blanket which takes an ink impression from a metal or other non-yielding printing plate or element and, in turn, prints the impression upon the print receiving surface. Very smooth prints can be made upon either smooth or rough surfaced papers by this method, but the solid colors lack depth or strength because the impression upon the paper is really a second step, offset from the first impression made upon the rubber blanket. This shortcoming, in a way, is true also of the individual dots or values that make up the halftone or color gradation areas, each lacking its real depth of color. Offset printing also has the disadvantage that it involves more steps, and therefore is slower in make-ready than direct printing. Furthermore, it is not as accurate in register for color work on account of variations in the surface speeds of the different cylinders of the press.

One object of this invention is to produce a planographic printing plate or element which is adapted for direct printing and will give the advantages but overcome the disadvantages above mentioned, of both the direct and offset methods of planographic printing. Other objects of the invention are to supply a planographic printing element having a permanent printing image on a yielding or resilient print-producing surface adapted to be inked and to print long editions by the direct method, and which will produce ink impressions that are full bodied in the solid color areas as well as in the case of the individual dots making up the values in lights and shadows, and at

the same time insure smooth, unbroken prints upon either smooth or rough surfaced paper and other print-receiving material; also to provide means whereby the steps and operations now required in offset printing are reduced in number, the presses needed to produce a high class product are simplified, and results are attained in time, cost and quality of work that are not possible by other known methods of printing. Still another object of the invention is to supply a practical method for producing planographic printing plates having the before mentioned characteristics and advantages.

The resilient or yielding printing element is made preferably by mounting suitable elastic or resilient material, such as a thin sheet or layer of rubber of fine quality, upon a base of metal or other material of a relatively inelastic nature adapted to prevent stretching, creeping or distortion of the resilient sheet when making prints from the printing element and to insure accurate register and stability of the resilient printing surface thus formed when printing therefrom. The sheet rubber or its equivalent can be mounted directly on a thin, metal plate or sheet, or on a cylinder, and secured thereon, as by cementing. Or a sheet of tough, even paper or film of other suitable character can be first cemented on the metal base and the sheet rubber cemented on the paper or film, which forms a binder between the rubber and metal and insures a firm, reliable connection of the rubber to the non-extensible base. Sheet rubber or other suitable material can be applied in like manner to the reverse or under side of the metal or base plate for the purpose of producing a cushion under the metal base carrying the resilient printing surface, or a thin piece of felt or other suitable material can be used alone or with a rubber or other sheet on the reverse side of the printing element, depending upon the nature of the work to be printed, as illustrated in the accompanying drawings in which,

Fig. 1 is a face view of a resilient surfaced printing plate illustrating one embodiment of my invention.

Fig. 2 is a section thereof indicating diagrammatically by raised portions thereon the ink-receiving portions of the printing surface.

Figs. 3 and 4 are views similar to Figs.

1 and 2 respectively, but showing a negative of the printing image of the plate shown in Figs. 1 and 2.

Figs. 5-14 inclusive are similar sections of 5 different modifications of the invention.

Fig. 15 is a diagrammatic view of a press equipped with a printing element according to my invention.

As shown in Figs. 1-5 inclusive, the printing element consists of a sheet 16 of yielding material, preferably rubber of fine quality, which forms the printing surface, and is secured by a suitable cement or binder 17 on a non-elastic or non-extensible base 18, which preferably is a thin metal plate. The raised and depressed portions indicating the printing image in Figs. 2 and 4 are greatly exaggerated for the purpose of illustration. In the actual element the surfaces 20 of the printing and non-printing portions of the plate are practically in the same plane, as in other planographic plates.

Fig. 6 shows similar rubber sheets 16 and 16^a, similarly secured on both faces of the 25 metal base plate 18. The rubber sheet 16^a on the reverse side of the metal plate forms a yielding cushion for the latter.

Fig. 7 shows a printing element similar to that shown in Fig. 6 except that the cushion 30 19 on the reverse side of the base plate is made of felt or analogous material.

In Fig. 8 the element is substantially the same as shown in Fig. 6, except that a binder 35 20 of paper or other suitable material is interposed between the rubber cushion 16^a and the metal plate 18. This forms a very secure bond between the metal and rubber.

Fig. 9 shows the use of a similar bond 40 20 in a printing element constructed as in Fig. 7, with a felt cushion 19.

Fig. 10 shows the use of such a bond 20 between the metal plate 18 and the rubber sheet 16 forming the yielding printing surface.

Fig. 11 illustrates an element like that shown in Fig. 10, but provided with a rubber cushion 16^a.

The element shown in Fig. 12 is similar to that shown in Fig. 11, except that a felt 50 cushion 19 is used.

Fig. 13 shows an element having a rubber printing surface 16 and rubber cushion 16^a, but employing a bonding ply 20 between the metal plate and each rubber sheet.

Fig. 14 shows a similar combination, except that the rubber cushion is replaced by a felt cushion 19.

Various different constructions of the printing element adapting it for different 60 desired results are thus shown in Figs. 5-14, but still other constructions of the printing element having the yielding printing surface and a base or strengthening part of a character adapted to prevent stretching 65 or distortion of the yielding printing part

could be used. It is also possible to mount the yielding material forming the printing surface directly upon a press cylinder or upon a tubular cylindrical base adapted to be mounted in a press, although the thin, 70 flexible plate formation of the printing element, as illustrated in the drawings, is considered preferable because of various practical considerations.

Different methods can be employed for 75 preparing the rubber or yielding surface of the printing element for printing therefrom, after first cleaning it in any suitable way, to remove all grease or other foreign matter therefrom. For instance, it can be washed 80 with a solution of muriatic or hydrochloric acid, or acetic acid and salt in water; or the surface can be scoured with any suitable scouring medium.

One method of preparing the printing 85 surface after cleansing it, is as follows:—

First, the surface is sensitized in one of the well known ways used for sensitizing photographic plates or films, then a photographic image or images is or are made 90 upon the sensitized rubber surface by exposing the light sensitive coating to light through a positive or negative by photographic contact or projection printing. A greasy or etch-resist solution is applied to 95 the surface of the plate or element, either before or after the exposure thereof to light, and the images are developed with a developing solution of a suitable character, depending upon the nature of the light sensitive coating. This developing solution penetrates the greasy or etch-resist solution and dissolves or removes those portions of the light sensitive coating which were not hardened or fixed by the light action and 100 leaves the underlying portions of the printing surface bare and clean. Then, an ink-repellent solution, such for instance as a nut gall or chromic acid solution, is applied to the printing surface, after which the surface is washed with water and wiped dry or nearly dry. This completes the preparation 110 of the surface.

If the element is not to be used for printing therefrom for some time, the printing 115 surface is preferably coated with gum and the gum coating rubbed down smooth and dry. Thereafter, when the plate is to be used for printing, the gum coating is removed by washing with clean water so as to 120 leave the printing surface as it was before the application of the gum. Since rubber does not oxidize by exposure to the atmosphere so readily as metal, the gumming of the surface, which is for the purpose of preventing oxidation, is not so essential with the described rubber printing surface as with a metal plate.

Another method of preparing the resilient printing surface is to make ink images upon 130

the rubber surface previously cleaned, as explained, by printing directly thereon from an original plate suitably inked, by laying down a lithographic transfer sheet carrying the inked images, or by other methods of applying an ink image on a rubber surface. An ink-repellent solution, such for example as before mentioned, is then applied to the printing surface, after which the surface is washed with water and wiped dry or nearly so. Water will then adhere to the uninked portions of the surface while the inked portions will repel the water, but will take ink. The surface can, therefore, be damped, inked and prints made therefrom after the manner of printing from the ordinary planographic printing plates.

The printing plate or element with the resilient printing surface prepared by either of the methods explained can be mounted upon a flat-bed press, or preferably on a cylinder A of a cylinder press, indicated diagrammatically in Fig. 15, which is suitably constructed so that the resilient printing surface is disposed on a circular line coincident with or slightly above the line known as the pitch circumference of a gear that drives the cylinder. The print-receiving paper or material B is held in position against the printing surface during printing to receive the inked impression therefrom, by an impression cylinder C having a similar surface diameter. The surface of the impression cylinder can be either hard or yielding, according to the requirements of the work to be printed, or the impression cylinder can be supplied with a resilient surfaced plate with images produced thereon, as before described, and this second plate can be inked and treated to yield impressions on the reverse side of the print-receiving sheet, thus operating as a perfecting press.

When printing from the resilient printing surface having the printing images formed thereon, as explained, the printing surface is damped by ordinary damping rollers or other means, so as to place a thin film of moisture over all portions of the surface except where it is repelled by the greasy ink images which, however, will readily take greasy ink from ordinary inking rollers and yield impressions directly upon paper or other suitable print-receiving material. If the greasy ink used is colorless, nonprintable, or not visible, then a water ink can be used to print from the grease repellent parts. The usual damping with water would not then be necessary.

Fig. 15 shows the printing element provided at its opposite ends with securing and registering bars 25 which are attached to and remain on the element. These bars are adapted to be removably secured in seats 26 on the press cylinder and to abut against

rigid parts on the seats or cylinder to accurately register the printing element both endwise and sidewise on the cylinder, as explained more fully in my Patent No. 1,391,117, dated Sept. 20, 1921.

I claim as my invention:—

1. A planographic printing element comprising a thin sheet of rubber having a printing surface provided with a permanent printing image the surface of which is substantially coplanar with said rubber surface, and a substantially non-extensible base to which said rubber sheet is attached and which prevents substantial stretching of said rubber when printing from said element, said base having a substantially uninterrupted surface forming a continuous backing for said rubber sheet.

2. A planographic printing element having a resilient rubber printing surface provided with ink-retaining and ink-repelling portions adapted when said surface is inked to form an ink image and adapted to produce ink impressions of said image, and a base to which said printing surface is attached and which prevents substantial stretching of said surface when printing therefrom.

3. A planographic printing element having a printing surface of rubber provided with ink-retaining and ink-repelling portions adapted when said surface is inked to form an ink image and adapted to produce ink impressions of said image, and means which prevent substantial stretching of said rubber.

4. A planographic printing element having a printing surface of rubber provided with a permanent printing image, the surface of which is substantially coplanar with said printing surface, and a substantially non-extensible base to which said rubber is attached and which prevents substantial stretching of said rubber, said base having a substantially uninterrupted surface forming a continuous backing for said printing surface.

5. A flexible planographic printing element comprising a thin sheet of rubber having a printing surface provided with a permanent printing image the surface of which is substantially coplanar with said rubber printing surface, and a thin flexible but substantially non-extensible base to which said rubber sheet is attached and which prevents substantial stretching of said rubber when printing from said element, said base having a substantially uninterrupted surface forming a continuous backing for said rubber sheet.

6. The process of making a planographic printing surface which is resilient in a direction normal to said surface but is substantially non-extensible in directions parallel with said surface, consisting in securing a

thin layer of resilient material such as rubber uniformly and continuously throughout the area of said resilient material on a flexible but substantially continuous and non-extensible base, forming a permanent printing image on said resilient printing surface substantially coplanar with said surface, and treating said resilient printing surface to cause the portions thereof not covered by said printing image to be ink-repellent.

7. The process of making a planographic printing surface which is resilient in a direction normal to said surface but is substantially non-extensible in directions parallel with said surface, consisting in securing a thin layer of resilient material such as rubber uniformly and continuously throughout the area of said resilient material on a flexible but substantially continuous and non-extensible base, coating the surface of said resilient material with a light-sensitive substance, producing by photography a printing image on said coated resilient surface and then treating said printing surface to cause the portions thereof not covered by said printing image to be ink-repellent.

8. The process of making resilient planographic printing surfaces, consisting in coating the surface of a resilient material such as rubber with a light sensitive coating, producing a photographic image on said sensitized surface by exposing the same to light through a photographic printing element, applying a greasy or etch-resist solution to said surface, developing said image with a developing solution, then applying an ink-repellent solution to said surface, and then washing said surface.

9. A flexible substantially non-extensible planographic printing element having a

printing surface of resilient material such as rubber provided with a printing image the surface of which is substantially coplanar with said printing surface and having a flexible substantially non-yielding uninterrupted smooth backing for said resilient material.

10. A flexible substantially non-extensible printing element comprising a thin facing sheet of a resilient material such as rubber, a thin flexible metal sheet forming a substantially uninterrupted smooth backing for said resilient facing sheet, and a thin fabric sheet interposed between and intimately attached throughout to said facing sheet and metal sheet.

11. A planographic printing element comprising a base providing a substantially continuous uniform backing, said base being composed of sheet material possessing flexibility but substantially not extensible in directions parallel to the plane of the sheet, a substantially co-extensive sheet of inherently resilient material, such as rubber, superimposed on said base, said resilient sheet having a direct printing surface provided with an ink-printing image, fixed on and substantially coplanar with said surface, said resilient sheet being substantially uniformly slightly compressible against said base in directions substantially normal to the printing surface to compensate for variations when under pressure, and means for securely attaching said base and resilient sheets uniformly and continuously throughout the areas of their adjacent surfaces whereby to substantially prevent any displacement of the resilient sheet in directions parallel to the surface thereof.

WILLIAM C. HUEBNER.
